MORRIS FARKAS, OF NEW YORK, N. Y., ASSIGNOR TO CASSIDY COMPANY, INC., OF LONG ISLAND CITY, NEW YORK, A CORPORATION OF NEW YORK.

DESIGN FOR A LAMP-STAND.

56,421.

Specification for Design. Patented Oct. 26, 1920.

Application filed May 27, 1920. Serial No. 384,741. Term of patent 7 years.

To all whom it may concern:

Be it known that I, MORRIS FARKAS, a citizen of the United States, residing at 922 Leggett avenue, in the city of New York, in the county of Bronx, State of New York, have invented a new and original and ornamental Design for a Lamp-Stand, of which the following is a specification, reference being had to the accompanying drawing, forming part thereof, and in which—

Figure 1 is a front elevation of a lamp stand constructed in accordance with this

design, Fig. 2 an elevation of the back of a mirror forming a portion of the same, and Fig. 3 a fragmentary top plan view of the base of the same.

I claim:

The ornamental design for a lamp stand, as shown.

MORRIS FARKAS.
